United States Patent Office

Des. 186,707
Patented Nov. 24, 1959

186,707

WATER CLOSET

Frederick Charles Harrison, Baildon, Shipley, England,
assignor to Shires & Co. (London) Limited, Guiseley,
England, a company of Great Britain

Application December 9, 1957, Serial No. 48,844

Claims priority, application Norway November 4, 1957

Term of patent 14 years

(Cl. D4—5)

The undisclosed side of the water closet is substantially the same in appearance as the side shown.

I claim:

The ornamental design for a water closet, as shown and described.
